UNITED STATES PATENT OFFICE

WADE H. REICHARD, OF ROCHESTER, NEW YORK, ASSIGNOR TO GENERAL RAILWAY SIGNAL COMPANY, OF ROCHESTER, NEW YORK

TRAIN CONTROL CAR ELEMENT

Application filed April 27, 1929. Serial No. 358,578.

This invention relates to automatic train control systems, and in particular concerns an inductive receiver for automatic train control systems of the alternating current intermittent inductive type, as disclosed, for example, in the pending application of Phillip X. Rice, Ser. No. 106,478, filed May 3, 1926, and in the application of W. H. Reichard, Ser. No. 358,577 entitled "Train control systems", filed April 27, 1929.

It is proposed to provide in accordance with the present invention, a compact and durable receiver structure designed to have a readily adjustable magnetic circuit.

The receiver is provided with a magnetic circuit so arranged that a given adjustment is not appreciably affected by vibration due to train operation or other cause.

Also, the receiver of this invention is so organized that it admirably meets the economic requirements of commercial production.

Other objects, purposes and characteristic features of the invention will be in part apparent, and in part pointed out, as the description thereof progresses.

In describing the invention in detail, reference will be made to the accompanying drawings in which:—

Fig. 1 is a side elevation showing a receiver embodying the present invention, as attached to a locomotive frame;

Fig. 2 is a side elevation of the receiver of Fig. 1, with certain parts in section to show the structure thereof;

Fig. 3 is a section on line 3—3 of Fig. 2 showing the adjustable core cross member;

Fig. 4 is a section on line 4—4 of Fig. 3 showing the details of the terminal box;

Fig. 5 is a section, rotated 180°, on line 5—5 of Fig. 3 and showing a top view of the adjustable core cross member;

Fig. 6 is a side elevation of Fig. 5; and

Fig. 7 is a perspective view of the receiver core members and coils, showing their interrelation and the apparatus directly associated therewith.

Fig. 8 is a fragmentary section on line 8—8 of Fig. 6, looking in the direction of the arrows.

The specific embodiment of the present invention is provided with inter-related parts which may be divided into three groups including, the means for mounting the receiver to a locomotive frame, the electro-magnetic structure, and the housing for inclosing the electro-magnetic structure.

Referring now to the drawings, there is shown a receiver R mounted in front of, and between, the wheels of the front pony truck of a locomotive frame L (see Fig. 1). The supporting means comprises a bracket BR which is securely attached to the frame L. A wash-board connection, such as disclosed in the patent to C. S. Bushnell, Pat. No. 1,710,655 granted April 23, 1929, is used to attach the receiver R to the bracket BR. This connection includes a support member 1, a corrugated plate 2, a plate 3, a bolt 4, a square bushing 5, and a nut 6. These parts are suitably arranged, so that the height of the receiver above the rails can be readily adjustable, and a given adjustment maintained by a bolt 7 with the usual lock nut.

The specific construction of the electro-magnetic structure of the receiver comprises a modified H shaped laminated core carrying thereon suitable primary and secondary coils (see Fig. 7).

The laminated core structure includes right and left hand members A and B respectively, (see Fig. 3) which are placed lengthwise of the receiver R, and which have three parallel portions connected by two offsets, giving a bridge effect appearance as seen in Fig. 2. This shape serves three purposes, namely, the end portions of the cores A and B are brought near the lower base of the receiver R, in such a position that the trackway device will have its greatest influence; the central upper portions of the cores A and B are raised to such a position that suitable fixed and adjustable cross members can be placed in convenient positions; the oblique or offset portions of the core members A and B furnish suitable sections for the primary and secondary coils P¹ and P², and S¹ and S² respectively.

The cross members or bridge of the core structure include cores C and D attached to a

holding member 8 by rivets 9 on the right and left hand sides respectively, as seen in Fig. 6. These cross members are mounted, so that they can be moved transversely in respect to core members A and B at the central portion of said core members A and B. At the right of the movable core members C and D are fixed core members G and H attached to a holding member 10, and also at the left of movable core members C and D are the fixed core members E and F attached to a holding member 11.

The general shape of the core members C and D is rectangular, with a triangular shaped portion cut away on one end of each of said core members C and D. The exact shape of the core members C and D is best seen in Figs. 5 and 6, which show how there is a varying amount of iron included within the magnetic bridge circuit as the holding member 8 with its core members C and D is moved transversely in respect to core members A and B. The movable core members C and D are mounted centrally with respect to cores A and B, with a non-magnetic metal strip 12 inserted between the milled surfaces of cores A and B and cores C and D for purposes to be hereinafter explained. Also, the fixed core members E and F, and G and H, are rectangular in shape. Core members G and H are mounted on the right side of the movable core members C and D and core members E and F are mounted on the left side of movable core members C and D with non-magnetic strips 32 and 39 between their lower milled surfaces and the core members A and B (see Fig. 6). It will be hereinafter explained how the fixed and movable core members are located with respect to the core members A and B.

The core member A (see Fig. 7) has the primary coil P^2 mounted upon its left hand offset, and the secondary coil S^1 mounted upon its right hand offset, while the core member B has the primary coil P^1 mounted upon its right hand offset and the secondary coil S^2 mounted upon its left hand offset. These coils P^1 , P^2 , S^1 and S^2 are mounted upon the core structure in a carefully insulated manner and so wedged that they will remain in permanent positions.

The primary coils P^1 and P^2 are energized from a suitable source, such as an alternator, in series with a tuning condenser C^1 , while the secondary coils S^1 and S^2 are connected in series with a control relay CR and a tuning condenser C^2 . The operation of this electro-magnetic structure, with its associated control devices, is completely set forth in the above referred to application of W. H. Reichard, Ser. No. 358,577.

The electro-magnetic structure including the core members and coils, as heretofore mentioned, is mounted in a housing, preferably of oak wood or bakelized duck com-

prising right and left hand members 13 and 14 separated by a central member 15. These housing members have recesses for the primary and secondary coils P^1 , P^2 , S^1 and S^2 with their respective lead wires, and have recesses to receive core members A and B and their associated parts.

With the core members A and B having their respective coils in position, placed within the central housing member 15, the right and left hand housing members 14 and 13, respectively, are placed in position and clamped by bolts 16, which pass through the recess bushings 18, housing member 13, core member B, housing member 15, core member A, housing member 14, and the recess bushing 18, and are made secure by nuts 17. It will be noted, that the recess bushings 18 fit into countersunk holes with but a slight outer ring protruding beyond the surface of the housing members. These recess bushings 18 provide cavities for the heads of bolts 16 and nuts 17 so that said heads of bolts 16 and nuts 17 can be below the surface of the housing members.

Non-magnetic metal boots 19 and 20 are placed over the ends of the housing members 13, 14 and 15, and also core members A and B. These boots 19 and 20 are held in position by wood screws 21. The coil cavities, which are not entirely filled by the coils, and all other parts of the casing are filled with insulating compound, so that, when cover board 22, made of micarta or other suitable insulating board, is placed in position, the coils of the receiver are completely sealed within the housing. There are suitable recesses in the cover board 22 to permit the fixed and movable core structures to be suitably positioned.

The support member 1 is a casting of suitable non-magnetic material such as phosphor-bronze, which provides support for the housing and core structures as well as furnishing a terminal box. This support member 1 also provides a space for the movable core member and provides depressions where the various bolts attach the housing members.

The holding member 8 is an inverted U shaped casting with the lamina of core members C and D riveted upon each side, as seen in Fig. 6. On each side of the center is a web 8^a , which incloses a space for receiving a rectangular nut 23, as seen in Figs. 5 and 6. These webs 8^a form a slot, so that the holding member 8 can move vertically, as seen in Figs. 3 and 6, although a bolt 29 passes through the slot formed thereby. This holding member 8 is placed in the cavity provided for it, in the support member 1, in such a manner that slots 8^b and 8^c in member 8, pass over the bosses 24 and 25 projecting down from said support member 1. A coil spring 26 is placed over bushings 27 and 28, with the bolt 29 passing through the support member 1,

bushing 27, coil spring 26, bushing 28, slot formed in web 8^a, rectangular nut 23, and the slot in web 8^a, and fits into a bushing socket 28¹ provided in the opposite side of support member 1. It is thus seen, that the holding member 8 is biased to the right, as seen in Fig. 3, by the coil spring 26, and is moved from the right hand extreme position, to the left by clockwise rotation of bolt 29. It will also be noted, that the bosses 24 and 25 act as guides for the holding member 8 as they fit in the slots 8^b and 8^c. The core members C and D are held firmly against the non-magnetic metal strip 12 by a coil spring 30 which is placed within a screw cap 31.

As best shown in Fig. 5, the head of bolt 29 is locked in position and protected against accidental or unauthorized operation, by a small box casing 27¹ closely conforming to, and fixed in place over the head of bolt 29, by bolts 29¹ furnished with a seal 29².

The fixed core members E and F are held against the core members A and B with the non-magnetic strip 39 intervening by screws 33¹ passing into housing member 15, and resiliently held in position by coil springs 36 received on studs 36¹ and restrained from movement by bolt 40, which passes through washer 41, the housing member 15, T shaped holding member 11, a hole in support member 1, and lock washer 46, after which a nut 47 is threaded into position. It is to be noted, that a countersunk hole is provided for the head of bolt 40 and washer 41 so that they will not protrude below the bottom surface of housing member 15.

In a similar manner, the core members G and H are held against the non-magnetic strip 32 by a bolt 33 which is passed through a washer 34, the housing member 15, T shaped holding member 10, a spacer 43 held to the support member 1, a hole in the support member 1, and lock washer 37, after which a nut 38 is threaded into position. The holding member 10 is held in position as is member 11, by screws 33¹ and springs 36, with the spacer 43 between the upper ends of the springs 36 and the support member 1.

Thus, the housing members and electromagnetic core structures are supported by support member 1, being further attached by bolts 48 which are passed through the housing member 15, the cover board 22, holes in support member 1, and lock washers 49, after which nuts 50 are threaded into position.

The terminal block 51 is held within a recess in the support member 1 by screws 52, which also hold a cover 53 to inclose the terminal connections within an insulated housing. The lead wires are brought into this insulated housing through coil spring bushings 54, while the lead wires going to the car carried apparatus are passed through a con-

duit fitting 55, and through a suitable conduit to the mechanism case.

It should be noted here, that the primary and secondary coils do not differ in structural characteristics, but rather in their electrical characteristics, such as their resistances, number of turns and so forth. It should further be noted that the non-magnetic strips 12, 32 and 39 form a permanent air gap between the respective core members which they separate. An advantage is thus obtained in that a slight variation in air gap due to vibration of a receiver does not change the reluctance of the magnetic circuit appreciably, as compared to the corresponding change which occurs, when the respective core members come in contact with each other. In other words, the difference in reluctance of the magnetic circuit due to a change from no air gap, to a slight air gap, is great, while the same slight change in an air gap when added to an existing air gap, does not cause a very great change in the reluctance of the magnetic circuit.

Also, from Fig. 5, it is seen that a very fine adjustment of the magnetic circuit can be obtained by varying the position of movable core members C and D in a direction transverse to core members A and B, particularly so, as one end of each of the core members C and D has what might be called tapering ends.

A receiver or car carried element has thus been devised which is composed of a modified H shaped core structure so arranged that the magnetic circuits can be readily balanced, and which also is of simple construction, and is rugged and durable and which will withstand such conditions as exist on railroad rolling stock.

It will be understood that the above given specific description shows but one form of device embodying the present invention, and has been given solely by way of illustration, and is not intended, in any manner whatsoever, in a limiting sense. It is obvious that this invention can assume many different physical forms, and is susceptible of numerous modifications, and all such forms and modifications are intended to be included by this invention, as come within the scope of the appended claims.

What I claim is:—

1. In a train control receiver, in combination, a magnetic core forming a partial magnetic circuit, and a magnetic bridge core member, nut and screw members for adjusting the position of the bridge member, and elastic means for retaining the parts in adjusted positions, whereby to vary the reluctance of said magnetic circuit, at will.
2. In a train control receiver, in combination, a magnetic core forming a partial magnetic circuit, means including, a bridge core member, nut and screw members for mov-

- ing the bridge member, and elastic means for retaining the parts in adjusted positions, for varying the reluctance of circuit core, at will, and sealable protective means for the operable part of the screw member for preventing tampering therewith.
3. In a receiver for train control systems, in combination, a magnetic core comprising separate spaced legs, a fixed bridge core interconnecting the legs, and a magnetic bridge core interconnecting the legs and adjusting means for moving the magnetic bridge core relatively to said legs.
4. In a receiver for train control systems, in combination, a magnetic core comprising separate spaced legs, a fixed bridge core interconnecting the legs, an adjustable magnetic bridge core interconnecting the legs, means for moving the magnetic bridge core transversely of said legs, and non-magnetic spacers between the said bridge cores and said legs for providing air gaps between the legs and the bridges.
5. In a receiver for train control systems, in combination, a magnetic core comprising separate spaced legs, a fixed bridge core interconnecting the legs, an adjustable bridge core interconnecting the legs, a carrier for said adjustable bridge core, and means for moving the carrier and its bridge core transversely of said legs to thus vary the reluctance of the magnetic path from one leg to the other.
6. In a receiver for train control systems, in combination, a magnetic core comprising separate spaced legs, a fixed bridge core interconnecting the legs, an adjustable bridge core interconnecting the legs, a carrier for said adjustable bridge, and nut and threaded bolt means for moving the carrier and its bridge transversely of said legs to thus vary the reluctance of the magnetic path from one leg to the other.
7. In a receiver for train control systems, in combination, a magnetic core comprising separate spaced legs, a fixed bridge core interconnecting the legs, and an adjustable bridge core interconnecting the legs, said bridge core, where it faces a leg, being tapered transversely of the leg to thereby accentuate the change in reluctance of the magnetic path from one leg to the other due to its being adjusted in position.
8. In a receiver for train control systems, in combination, a magnetic core comprising separate spaced legs, a fixed bridge core interconnecting the legs, an adjustable bridge core interconnecting the legs, a carrier for said adjustable bridge, and nut and threaded bolt means for moving the carrier and its bridge transversely of said legs to thus vary the reluctance of the magnetic path from one leg to the other, said bridge core, where it faces a leg, being tapered transversely of the leg to thereby accentuate the change in re-

luctance of the magnetic path from one leg to the other as it is adjusted in position.

9. In a train control receiver, a generally H shaped magnetic core, primary and secondary coils on the core, and an adjustable bridge core constituting the cross bar of the H and including a carrier and a core portion on each side of the carrier, the core portions being tapered at an end that overlies a leg of the H.

10. In a train control receiver, a generally H shaped magnetic core, primary and secondary coils on the core, and an adjustable bridge core constituting the cross bar of the H and including, a carrier, a core portion on each side of the carrier, the core portions being tapered at an end that overlies a leg of the H, a socket in the carrier for retaining a threaded nut, an adjusting bolt threaded into the nut, resilient means biasing the bridge in a direction transverse to the leg parts of the core, the bridge being movable against the resilient means by means of said nut and bolt.

11. In a train control receiver, a generally H shaped magnetic core, primary and secondary coils on the core, and an adjustable bridge core constituting the cross bar of the H and including, a carrier, a core portion on each side of the carrier, the core portions being tapered at an end that overlies a leg of the H, a socket in the carrier for retaining a threaded nut, an adjusting bolt threaded in the nut, resilient means biasing the bridge in a direction transverse to the leg parts of the core, the bridge being movable against the resilient means by means of said nut and bolt, said bolt being loosely received in the carrier, a casing inclosing the carrier and loosely receiving said bolt, resilient means pressing the carrier and its cores toward the leg portions of the core, and a cap connectable to the casing to prevent tampering with said bolt.

12. In a train control receiver, in combination, a magnetic core in the general form of an H, a primary and a secondary winding on each leg of the core and on opposite sides of the cross bar of the H, and means for adjusting the said bar of the core relatively to the legs to vary the magnetic coupling between primary and secondary windings on different legs.

In testimony whereof I affix my signature.
WADE H. REICHARD.
